CLAIM

The ornamental design for a solder splint, as shown and described.

DESCRIPTION

FIG. 1 is a front perspective view of a solder splint showing our new, original and ornamental design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The dash-dash broken lines shown in the drawings illustrate portions of the solder splint that form no part of the claimed design. The dash-dot-dash broken lines show boundary lines and form no part of the claimed design.
